UNITED STATES PATENT OFFICE.

NILS GUSTAF ENSTRÖM, OF STOCKHOLM, SWEDEN, ASSIGNOR, BY DIRECT AND MESNE ASSIGNMENTS, OF TWO-THIRDS TO JOHN PHILIP DAHLLÖF AND ONE-THIRD TO KARL JOHAN HELLSTROM, BOTH OF NEW YORK, N. Y.

ARTIFICIAL FOOT.

1,119,258.

Specification of Letters Patent.

Patented Dec. 1, 1914.

Application filed December 6, 1913, Serial No. 805,051. Renewed October 22, 1914. Serial No. 867,961.

To all whom it may concern:

Be it known that I, NILS GUSTAF ENSTRÖM, a citizen of Sweden, and resident of the city of Stockholm, in the county of Stockholm, Sweden, have invented certain new and useful Improvements in Artificial Feet, of which the following is a specification.

The present invention has reference to the manufacture of artificial limbs and contemplates the production of an improved appliance pertaining to this art which shall be particularly well adapted to take the place of an amputated foot, or else can be used as an extension to an artificial leg, embodying in either case the features necessary to afford the requisite comfort to the wearer and retain the shapeliness of his (or her) footgear.

The invention consists in certain structural details, combinations and arrangements of parts, whereby some material advantages over analogous devices of anterior date are gained, and the appliance is rendered less complicated or cumbersome, less expensive to make, more convenient to use, and practically noiseless in action, all as will hereinafter clearly appear.

In order that the invention may be more readily understood, reference will now be made to the drawing hereto annexed wherein—

Figure 1 is a sectional plan of the preferred embodiment of the invention taken on the line 1—1 of Fig. 2, and Fig. 2 is a sectional elevation of the same, on the line 2—2 of Fig. 1.

In the form illustrated herein, the invention comprises the following named essential elements, to wit; a part 11, constituting the heel of the artificial foot; a second larger part 12, reversely curved therefrom and forming the forward pedal portion; a hinge connection 13, between the said two parts; and an elastic device 14, attached to this connection and controlling the movements of the parts with relation to each other.

The part 11, as shown, consists of a U-shaped piece, placed horizontally edgewise, with its curve directed rearward, and is of suitable height to afford the required lateral support to the counter of the shoe within which it is to be fitted and placed. This

part may be attached to the leg (natural or artificial) of the wearer, in various ways, the preferred one of which is shown herein and will next be described.

A stirrup 15 is secured to a collar 16 adapted to embrace the stub end of the leg, and is suspended therefrom so that its transverse member will lie horizontally under and across the part 11, preferably at the central part thereof, with the opposite side members of the stirrup extending upwardly in the same plane. The cross member of the stirrup enters notches 17 formed in the lower edges of the part 11, which notches are of sufficient height and length to allow play of the member therein. Centrally above these notches and the transverse member of the stirrup, the vertical members of the latter are joined to the opposite side members of the part 11 by loosely fitted rivets 18, performing the function of pivot pins between the said part and stirrup. Normally, that is, in an idle position, the transverse member of the stirrup and the lower edge of the part 11 will lie level with the ground, but the arrangement is such that the part is movably connected to the stirrup by the rivets 18, and the former obtains a slight rocking movement thereon with relation to the latter, due to the clearance afforded by the notches 17. Therefore, the heel of the artificial foot is movable *per se*, to wit, independently of the leg connection, as also of the other parts, and since it receives the first impact as the foot usually touches the ground the movement here referred to simulates the yielding action of the natural heel which is conducive to soft and light treading.

Like the part 11, hereinbefore described, the part 12 is U-shaped, or substantially so, and similarly placed, though it is of less height, of greater length, and reversed in end position. The latter named part is designed to replace the sole and digital extremities of the natural foot in the shoe, and therefore its curve is directed forward and its sides are made more or less sinuous to follow the outline of the position which would naturally be occupied in the shoe by the fore-part of the foot, if present. Proper lateral support is thereby afforded to the toe and sides of the shoe. Further support therefrom is given to the shoe-upper through the

instrumentality of a bridge or arched piece 19, rigidly secured at its edges to the sides of the bow 12, for instance by means of rivets 20.

5 As best seen in Fig. 1, the ends of the two parts 11 and 12 overlap one another and are united by the before-named hinge-connection 13, which may consist of a spindle or hinge pin passed transversely through registering holes in the meeting ends of the said parts and upset or formed with retaining heads on the outside, as at 21. This spindle or hinge-pin forms a fulcrum to the two parts. United in this manner, the parts 11 and 12 are capable of interrelative movement in adjacent vertical planes. Their movement however, is limited by rivets 22, secured to the opposite ends of the part 12 and passed through vertical slots 23, provided in the corresponding ends of the bow 11, immediately in rear of the hinge connection. The slots are indicated by dotted lines in Fig. 2.

By preference, the aforesaid elastic device is composed of a plurality of springs, 25 collectively designated by the numeral 14. These springs are coiled intermediately of their lengths around the spindle 13, about which they may have each a couple of convolutions as shown. They are placed preferably at equal distances apart on the spindle, between the opposite sides of the parts 11 and 12, and their ends are led from the underside of the spindle oppositely toward the curves of the parts, forward and rearward respectively. Forwardly, the ends of the several springs pass loosely through apertures 24, provided in a cross-brace 25, secured at its ends to the inner sides of the 30 part 12. At the rear, the extremities of the springs are first run outwardly and thence inwardly through similar holes 26, 27, located above one another in the curve of the bow 11, these extremities of the springs being bent for the purpose, as at 28, Fig. 2. The springs 14 are thus anchored to the part 11, and slidably connected with the cross brace of the part 12. Arranged in this manner, the springs are caused to bear 35 from opposite sides of the spindle 13, upon both parts 11 and 12, which they press downward to normal inactive positions. When, however, a movement is imparted to either part, the springs control the same in such a way as to insure at all times an elastic flexure and rebound of parts, affording a certain measure of comfort in use and practically noiseless in operation. An outer covering 29, of leather or other suitable material, may be employed, if desired, to incase this improved artificial foot and protect the several parts thereof from dust or otherwise shield them against outside interference.

65 It is understood that various modifica-

tions can be effected in the construction of the above described appliance, especially in the means provided for limiting the movements of the parts 11 and 12 and in the arrangement of the springs, and consequently the right is reserved to make alterations therein, as well as all changes that come within the scope of the invention or embody its underlying principle.

Having described my invention what I 75 desire to secure by Letters Patent and claim is:—

1. An artificial foot comprising oppositely curved parts hingedly connected one with the other, said parts constituting the 80 heel and sole of the foot respectively.

2. An artificial foot comprising oppositely curved parts respectively representing the heel and forward part of the foot, a hinge connection between said parts, and an 85 elastic device bearing upon said heel and said forward part from opposite sides of said connection.

3. An artificial foot comprising a heel, a forward portion loosely connected therewith, a hanger suspending said heel from the leg, and a connection between said hanger and the heel permitting movement of the latter independently of either the hanger or the forward portion.

4. An artificial foot comprising a part constituting the heel, a stirrup secured to the leg and having its transverse member movably fitted across said part, a pivotal connection between the opposite sides of the 100 part and the sides of said stirrup, and a forward foot portion hingedly connected with the ends of the part in advance of said pivotal connection.

5. An artificial foot comprising a part 105 forming the heel, an oppositely curved part constituting the sole and forward extremity of the foot, said parts overlapping at the ends, a spindle passing loosely through said overlapped ends, and one or more springs 110 or coiled around said spindle, the spring or springs being anchored at one end to one part and slidably connected at the other end with the other part.

6. An artificial foot comprising hingedly 115 connected parts curved outwardly in opposite directions, said parts respectively constituting the heel and sole, a spindle joining the ends of said parts loosely together, a brace extending transversely of the forward 120 part, and one or more springs coiled about said spindle, the spring or springs being anchored at one end to the rear part and having a sliding engagement at the other end with said brace.

7. An artificial foot comprising parts curved in opposite directions and having their ends lapped over one another, a spindle hingedly connecting the overlapped ends of said parts, and means for limiting the 130

movements of the parts relatively to each other.

8. An artificial foot comprising reversely curved parts hingedly connected one with the other, an elastic device bearing upon said parts on opposite sides from the hinge thereof, and a pin-and-slot connection between the ends of the parts limiting their movements about said hinge.

10 9. An artificial foot comprising a member having its lower edge of substantially bowed curvature, a longer fore-member of similar

curvature hinged thereto, an attachment for the leg to which one member is pivoted independently of the other, and resilient means acting upon both members tending to maintain them level.

Signed at the city of Stockholm, in the county of Stockholm, Sweden, this fourth day of November, A. D. 1913.

NILS GUSTAF ENSTRÖM.
